CLAIM

The ornamental design for a clock, substantially as shown and described.

DESCRIPTION

FIG. 1 is a front perspective view of a clock, showing our design.

FIG. 2 is a front view of the clock of FIG. 1.

FIG. 3 is a back view of the clock of FIG. 1.

FIG. 4 is a right side view of the clock of FIG. 1.

FIG. 5 is a left side view of the clock of FIG. 1.

FIG. 6 is a top view of the clock of FIG. 1; and,

FIG. 7 is a bottom view of the clock of FIG. 1.

The broken lines illustrate features and surfaces that form no part of the claimed design.
